UNITED STATES PATENT OFFICE.

EDWARD W. ISOM, OF SCARSDALE, NEW YORK, ASSIGNOR TO SINCLAIR REFINING COMPANY, OF NEW YORK, N. Y., A CORPORATION OF MAINE.

ART OF CRACKING HYDROCARBON OILS.

Application filed May 21, 1927. Serial No. 193,191.

This invention relates to improvements in the cracking of heavier hydrocarbon oils, such as gas oil or kerosene, in order to produce therefrom lighter hydrocarbon oils, such as gasoline or pressure distillate. The invention relates particularly to improvements in cracking operations carried out in externally heated, single pass, tubular oil cracking stills. In referring to single pass cracking operations, reference is made to cracking operations in which the oil supplied is circulated but once through the oil heating tubes of the still. The invention includes operations in which vaporized fractions are refluxed and recirculated through the oil heating tubes, but it is to be distinguished from operations in which the fresh oil itself or any unvaporized portion thereof is recirculated through the heating tubes. This application is in part a continuation of my prior application filed August 28, 1922, Serial No. 584,711.

The invention provides an improved method of cracking different grades of hydrocarbon oils in which each grade of oil is treated under conditions most advantageous for the cracking of that particular grade of oil and in which the several operations are combined in such a manner that a greater yield, better quality of product and more efficient operation may be obtained than it is possible to secure by the separate treatment of the individual grades of oil or a similar treatment of the oil mixture. The process of the invention is particularly advantageous in connection with the simultaneous treatment of relatively heavy hydrocarbon oils, such as gas oil or fuel oil, and of lighter and more refractory oils, such as kerosene or rerun pressure distillate bottoms. In the cracking of the more refractory hydrocarbon oils, for example, kerosene or very light gas oils, it is advantageous to use a higher temperature to produce the desired cracking reaction, say to produce gasoline, than is commonly used in the treatment of heavier oils, and treatment of the heavier grades of hydrocarbon oils at the temperatures required to crack the more refractory constituents of lighter grades within commercially practicable periods of time results in the formation of excessive quantities of fixed gases and carbon or coke.

In the combined treatment of different grades of oil according to the present inven-

tion, a stream of the more refractory lighter oil is passed once through a heating conduit and heated therein to a cracking temperature and the hot products from the heating conduit are discharged directly into a body of oil to which less refractory heavier oil is supplied, this body of oil is maintained at a cracking temperature, vapors are taken off from this body of oil and subjected successively to two refluxing operations, in the first the vapors are cooled and partly condensed by indirect heat exchange with fresh less refractory heavier oil supplied directly to the body of oil, in the second the vapors are further cooled and condensed by indirect heat exchange with fresh more refractory lighter oil, and reflux condensate from both refluxing operations together with fresh more refractory lighter oil preheated in the second refluxing operation is supplied to the heating conduit. The body of oil may be heated externally as well as internally by the hot products discharged into it from the heating conduit, but it is advantageously externally unheated and heated internally only.

At the higher temperatures employed in cracking the more refractory oils it is essential for safety and efficiency of operation to protect the heating tubes against overheating and the formation of carbon deposits therein and at the same time to maintain a high average temperature differential between the heating gases and the heat transferring surfaces. In the operation of the present invention the deposition of carbon in the heating tubes is avoided by circulating therethrough only the more refractory oils which do not cause excessive carbon formation at the temperatures employed and avoiding the recirculation of unvaporized oil which has been once subjected to cracking conditions and which accordingly contains, in solution and in suspension, pitch-like constituents, while a high average temperature differential between the heating gases and the heat transferring surfaces is maintained and excessive local overheating avoided by recirculating a portion of the heating gases which have passed over the heating tubes countercurrent to the flow of oil therethrough and admixing them with the hot products of combustion from the firebox to temper the latter prior to their contact with the oil containing tubes. By recirculating

a portion of the heating gases the volume and accordingly the velocity of the heating gases contacting with the heating tubes is increased. The increased velocity promotes 5 an increase in the rate, and a more uniform distribution of the heat absorption throughout the bank of heating tubes. Thus, the extremely high temperatures necessary for most efficient combustion of the fuel used 10 may be permitted without subjecting the oil containing tubes to contact with heating gases at excessive temperatures while at the same time a large portion of the heat contained in the products of combustion is efficiently transmitted to the oil being treated. 15

The higher temperature used to crack the lighter and more refractory hydrocarbon oil tends to promote the formation of fixed gases and unstable, unsaturated compounds, 20 the presence of which is objectionable in the finished product. In the operation of the present invention, however, in which the lighter oils are separately heated to their cracking temperature and subsequently introduced into a body of heavier oil maintained at the cracking temperature, the unsaturated constituents formed in the first operation apparently tend to react with constituents of the body of hot heavier oil to 25 form more saturated compounds. An increased yield of constituents suitable as components of the desired gasoline or pressure distillate is obtained and the formation of fixed gases and unstable, unsaturated 30 compounds reduced.

The additional fresh oil supplied to the body of heavy oil is advantageously pre-heated to substantially the temperature of the liquid body before its introduction 40 thereinto and the amount of heat required to be supplied externally to the liquid body in order to maintain it at the cracking temperature thereby further materially reduced. In some cases the application of external 45 heat to the reservoir may be dispensed with entirely, thereby avoiding any danger incident to the formation of heat insulating carbon deposits on the heated surfaces of the reservoir. The additional fresh heavy 50 oil introduced to the reservoir may advantageously be passed in countercurrent flow and in indirect heat exchanging relation with the vapors generated in the cracking operation before the latter are permitted 55 to cool appreciably. The fresh oil may thus be preheated to a temperature approaching the temperature of the liquid body to which it is introduced and the vapors refluxed by the cooling effect of the fresh oil. The 60 vapors remaining uncondensed may advantageously be subjected to a further refluxing operation in indirect heat exchanging relation with the fresh oil and this further refluxing operation controlled by regulating 65 the supply of the fresh lighter oil thereto

so that the desired gasoline product or pressure distillate may be directly produced without subsequent redistillation. The reflux condensates from both refluxing operations together with the fresh lighter oil supplied to the latter refluxing operation may be returned directly to the single pass heating conduit and additional lighter oil may be independently supplied therewith as described. It will be noted, however, that neither the heavier oil itself nor any of its unvaporized constituents are permitted to pass through the heating conduit with the more refractory constituents. 70 75

The invention will be further described 80 in connection with the accompanying drawings which illustrate, in a diagrammatic and conventional manner in elevation and partly in section, an apparatus adapted for the practice of the process of the invention, but 85 it is intended and will be understood that this further description and illustration are for the purpose of exemplification, but the invention is not limited thereto. 90

In the drawings:

A single-pass externally heated, tubular cracking still or heater is shown discharging into a shell still or reservoir from which the vapors of the cracked oil are taken off. The single-pass cracking still or heater comprises 95 a furnace 1 in which a battery of heating tubes 2 are arranged. Oil is forced through the heating tubes by means of a pump 3, entering the heating tubes through connection 4 and, after passing once therethrough, 100 being discharged through connection 5. The heating furnace 1 is provided with a firebox 6 and a stack flue 7, heating gases being circulated from the firebox through the heating furnace over the oil-containing 105 heating tubes therein to the stack flue. The firebox 6 is provided with means for burning the fuel employed to supply the heat used in the cracking operation. A burner for gaseous or liquid fuel is shown at 8. Before 110 the hot products of combustion in the firebox 6 come in contact with the oil heating tubes 2 in the furnace 1, they are admixed with a part of the heating gases which have passed over the oil heating tubes and which are returned through connection 9. The connection 9 is provided with an inlet 10 adjacent the exit to the stack flue from the furnace and with an outlet 11 through which the heating gases withdrawn from near the outlet of the furnace are returned and admixed with the hot products of combustion. The return connection 9 includes a blower 12 which may be operated by a steam jet 115 120 or other suitable means for maintaining circulation of the returned heating gases. 125

The oil forced through the heating tubes 2 includes fresh oil and constituents refluxed from vapors of the cracked oil discharged from the single pass cracking still or heater. 130

Fresh oil, of a heavier character, supplied from receptacle 27 by means of pump 34, is passed in indirect heat exchanging relation with the vapors in reflux tower 21 and then introduced into the body of oil in the reservoir 18 through connection 28 and pipe 29. The heat exchange in the reflux tower 21 cools and partly condenses the vapors and preheats the fresh oil supplied directly to the reservoir 18. Additional refluxing of the vapors may be effected in reflux tower 21 by passing therethrough an amount of fresh oil in excess of that supplied to the reservoir 18 and discharging this excess through connection 31. An amount of fresh oil, of a heavier character, in excess of that passed in heat exchanging relation with the vapors in reflux tower 21 may be supplied directly to the reservoir 18 by means of by-pass connection 30. During periods when fresh oil is not supplied to the reservoir 18, as at the beginning or end of a run, the reflux tower 21 may be cooled by oil circulated therethrough and discharged through connection 31. Fresh oil, of a lighter character, supplied from receptacle 33 by means of pump 35, is passed in indirect heat exchanging relation with the vapors in reflux tower 22, the vapors being thereby further cooled and condensed and the fresh oil preheated, and the thus preheated fresh oil is discharged into receptacle 16. By-pass connection 38 is provided between connections 36 and 37 to and from the reflux tower 22 to permit supply from receptacle 33 to receptacle 16 of an amount of the fresh oil in excess of that passed through the reflux tower 22. Vapors from reservoir 18 escaping through connection 20 pass first through the reflux tower 21 and then through the reflux tower 22 from which vapors remaining uncondensed escape through connection 23 to a condenser (not shown) in which the vapors of the cracked oil, forming the desired cracked distillate, are condensed. Reflux condensate from both tower 21 and tower 22 collects in receptacle 16. This reflux receptacle 16 may be insulated, and the reflux condensate, together with admixed fresh oil may be supplied therefrom to the heating tubes 2 at a more or less elevated temperature.

The oil mixture collecting in receptacle 16, including reflux condensate from the refluxing operations carried out in both reflux towers and fresh lighter oil preheated in the second refluxing operation, is supplied to the pump 3 through connection 17 and forced thereby through the heating tubes 2. Additional fresh oil, of a lighter character, may be supplied to the heating tubes in admixture with the oil from receptacle 16 by means of pump 3 from tank 14 through connection 15, or a separate pump may be used for supplying such additional fresh lighter oil through the heating tubes. The hot products discharged from the single pass heater through connection 5 are introduced into the body of oil in the reservoir 18 through pipe 19. The hot products discharged into the reservoir 18 through pipe 19 supply heat thereto and also assist in maintaining uniform conditions throughout that body by the agitation provided. Additional heat may be supplied to the reservoir 18 by means of furnace 32, for example to balance radiation losses, or, and more advantageously, this reservoir may be externally unheated and the body of oil therein heated internally only by the hot products discharged from the single pass heater. The reservoir 18, particularly where it is heated internally only, and the connections between the single pass heater and the reservoir, may with advantage be insulated to prevent heat loss. A connection 26 is shown for withdrawing tar and fluid residues from the reservoir 18. The unvaporized residue of the oil discharged into this reservoir from the single pass heater and the unvaporized residue of the fresh heavier oil independently introduced into the reservoir may be discharged through this connection. Pressure in the system may be maintained and regulated by valve 24 arranged between the reservoir 18 and the reflux towers 21 and 22, or by valve 25 arranged between the reflux towers and the condenser, or by suitable valves arranged beyond the condenser. The pressure in the reservoir 18 may be maintained, for example, in the neighborhood of 90 to 125 pounds per square inch.

As an example of one particularly advantageous method of operation of the apparatus illustrated in the drawings, in the combined treatment of a heavy gas oil, a light gas oil and a kerosene character distillate, according to the invention, the lightest or kerosene character distillate may be supplied from the receptacle 14 directly to the single-pass heating conduit 2 where it is heated to a temperature of from about 800° to 1200° F. The heavy gas oil may be supplied from the receptacle 27 by the pump 34 to the heat exchanger or reflux tower 21 and from thence to the reservoir 18 through connection 28 and pipe 29. The light gas oil may be supplied from the receptacle 33 by pump 35 to the reflux tower 22. The body of oil in the reservoir 18 may advantageously be maintained at a temperature of 700° to 850° F. The vapors liberated in the reservoir 18 pass successively through the reflux towers 21 and 22. The vapors in the reflux tower 22 are subjected to a refluxing operation by indirect heat exchange with the light gas oil supplied thereto from receptacle 33 and the light gas oil preheated thereby. The head temperature of the tower 22 may be regulated by the amount of

fresh oil supplied thereto, to produce a distillate having the desired end point. All of the lightest or kerosene character distillate may thus be required to pass through 5 the single pass heating conduit where it is subjected to the highest temperatures, and vaporization and escape of the lighted un-cracked constituents thereof without being subjected to the cracking conditions prevented.

The present invention is of special value in connection with the treatment of fresh oil stocks relatively free from constituents suitable as components of the desired distillate product but which nevertheless are of a closely similar character. In carrying out the invention, such stocks may be preheated by indirect heat exchange with the vapors in the second refluxing operation, that carried out in reflux tower 22 in the apparatus illustrated, and the vapors thereby cooled and refluxed, without any possibility of entrainment of such fresh oil in the vapors escaping from the refluxing operation. A rerun pressure distillate bottoms, remaining after separation of gasoline from a pressure distillate by redistillation, for example, may be handled advantageously in carrying out the present invention by passing it in indirect heat exchanging relation with the vapors in the second refluxing operation and then forcing it, in admixture with reflux condensate, through the single pass heater into the body of oil in the reservoir. In carrying out the present invention, it will be noted that while the preheated fresh oil from the second refluxing operation may be admixed with reflux condensate therefrom the mixture does not take place within the refluxing operation itself.

It is apparent that various modifications of the process embodying the invention may be made, for example, in the combined treatment of two grades of oil, the heavier oil may be supplied from the container 27 to the reservoir 18 while the lighter oil may be supplied entirely through the reflux tower 22 from the receptacle 33 or part of the lighter oil may be directly introduced into the heating conduit 2 from the receptacle 14 or supplied from receptacle 33 through connection 38. When possible, however, it is advantageous to regulate the refluxing operation as desired by the introduction of a portion of the lighter oil to the reflux tower 22 and to introduce any excess of the lighter oil, above that required to produce the desired refluxing action, directly into the heating conduit.

I claim:

1. An improved process for cracking hydrocarbon oils comprising passing a stream of oil once through a heating conduit and heating it to a cracking temperature therein, discharging the hot products from the heat-

ing conduit directly into a body of oil maintained in a reservoir at a cracking temperature, taking off vapors from the reservoir and subjecting them successively to a first and a second refluxing operation, passing 70 fresh relatively refractory oil in indirect heat exchanging relation with the vapors in the first refluxing operation and thereby cooling and refluxing the vapors and pre-heating the fresh oil, supplying fresh oil so 75 preheated to the body of oil in the reservoir, passing fresh relatively more refractory oil in indirect heat exchanging relation with the vapors in the second refluxing operation thereby cooling and refluxing the vapors and 80 preheating this fresh oil, and forcing reflux condensate from both refluxing operations together with fresh oil preheated in the second refluxing operation through said heating 85 conduit.

2. An improved process for cracking hydrocarbon oils comprising passing a stream of oil once through a heating conduit and heating it to a cracking temperature therein, discharging the hot products from the heating conduit directly into a body of oil maintained in a reservoir at a cracking temperature, taking off vapors from the reservoir and subjecting them successively to a first and a second refluxing operation, passing 90 fresh relatively refractory oil in indirect heat exchanging relation with the vapors in the first refluxing operation and thereby cooling and refluxing the vapors and pre-heating the fresh oil, supplying fresh oil so 95 preheated to the body of oil in the reservoir, passing fresh relatively more refractory oil in indirect heat exchanging relation with the vapors in the first refluxing operation and thereby cooling and refluxing the vapors and pre-heating the fresh oil, supplying fresh oil so 100 preheated to the body of oil in the reservoir, passing fresh relatively more refractory oil in indirect heat exchanging relation with the vapors in the second refluxing operation thereby cooling and refluxing the vapors and 105 preheating this fresh oil, and forcing reflux condensate from both refluxing operations together with fresh oil preheated in the second refluxing operation through said heating 110 conduit, the body of oil in the reservoir being externally unheated but heated internally by the hot products discharged into it from said heating conduit.

3. An improved process for cracking hydrocarbon oils comprising passing a stream of oil once through a heating conduit and heating it to a cracking temperature therein, discharging the hot products from the heating conduit directly into a body of oil maintained in a reservoir at a cracking temperature, taking off vapors from the reservoir and subjecting them successively to a first and a second refluxing operation, passing 115 fresh relatively refractory oil in indirect heat exchanging relation with the vapors in the first refluxing operation and thereby cooling and refluxing the vapors and pre-heating the fresh oil, supplying fresh oil so 120 preheated to the body of oil in the reservoir, passing fresh relatively more refractory oil in indirect heat exchanging relation with the vapors in the first refluxing operation and thereby cooling and refluxing the vapors and pre-heating the fresh oil, supplying fresh oil so 125 preheated to the body of oil in the reservoir, passing fresh relatively more refractory oil 130

in indirect heat exchanging relation with the condensate from both refluxing operations thereby cooling and refluxing the vapors and preheating this fresh oil, and forcing reflux condensate from both refluxing operations together with fresh oil preheated in the second refluxing operation through said heat- ing conduit, the stream of oil passed through the heating conduit being heated therein to a cracking temperature higher than that main- 10 tained in the body of oil in the reservoir.
